Primary Examiner—Robin Webster*Assistant Examiner*—Karen E. Patterson(74) *Attorney, Agent, or Firm*—Brinks Hofer Gilson & Lione(57) **CLAIM**

We claim the ornamental design for a surveillance hard disk recorder, as shown and described.

DESCRIPTION

FIG. 1 is a top perspective view of surveillance hard disk recorder of the present invention;

FIG. 2 is a front view thereof;

FIG. 3 is a top view thereof;

FIG. 4 is a bottom view thereof;

FIG. 5 is a first side view thereof;

FIG. 6 is a second side view thereof; and,

FIG. 7 is a rear view thereof.
